UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

ROCK-DRILL VALVE.

Application filed May 27, 1925. Serial No. 33,105.

This invention relates to fluid actuated rock drills, but more particularly to an improved valve and valve construction which may be conveniently located rearwardly of the cylinder.

The objects of the invention are to secure a valve construction in which the distributing valve for the rock drill may surround the water tube of the machine and slide transversely relatively to said water tube. In a machine in which automatic rifle bar rotation is provided for the drill steel the valve will preferably be located rearwardly of the rotation head and ratchet ring so that the valve is readily accessible and the valve construction does not materially increase the length of the machine.

Further objects will hereinafter appear and the invention is shown in one of its preferred forms in the accompanying drawings, in which

Figure 1 is a longitudinal sectional elevation of so much of a rock drill as will serve to illustrate the invention,

Figure 2 is a similar view with the piston and valve in a different position,

Figure 3 is a transverse sectional plan view on the line 3—3 of Figure 1 looking in the direction of the arrows, and

Figure 4 is a detail side elevation of the valve.

Referring to the drawings, the cylinder A is provided with the reciprocating piston B having the fluted forward extension or shank C. The usual rifle bar D cooperates with the piston. The cylinder is provided with a free exhaust E located centrally of the ends of the cylinder and controlled only by the piston. The usual water tube F extends through the rifle bar D and piston B and the pressure fluid supply of the machine is controlled by the throttle valve G in the back head H. Between the back head H and the back cylinder head block J is arranged a head plate K and the valve L is located in the valve chamber O, in this instance located within the back head H.

The valve L is in the form of a rectangular slidable block having a hollow central portion P surrounding the water tube F with sufficient clearance to permit the block to slide back and forth. A sleeve Q is preferably provided over a portion of the water tube F and is seated in the back head H and plate K in order to form a tight connection.

A member or members R constituting a valve box within the back head also forms stops for the valve to limit its travel and passages S in said valve box connect the valve chamber O with the inlet passages T and U leading respectively to the cylinder inlet ports V and W at opposite ends of the cylinder.

The valve L is of the current thrown type and controls only the inlet passages and ports to the ends of the cylinder. The valve as shown is of an appreciably greater length than width or height, and the longer sides form seating surfaces of the valve alternately exposed to reduced pressure in the cylinder. The valve is provided with the flanges X at top and bottom at each end having recesses Y for the passage of pressure fluid through the flanges and these recesses Y are of such total cross sectional area with relation to the cross sectional area of the cylinder inlet passages S that the flow or current of pressure fluid through the recesses tends to close the valve at the side from which the pressure is reduced in the operation of the piston. The flanges X are preferably located slightly inwardly from the sides of the valve to form opposed symmetrical pressure areas X' on said flanges and which pressure areas are constantly exposed to pressure fluid from the source of supply for throwing the valve.

In the operation of the device let it be assumed that the piston, as shown in Figure 1, is starting to travel on its forward stroke and the valve is in the position indicated in said figure. In such case pressure fluid is supplied at the throttle G which should be open passes to the valve chamber O and thence through the recesses Y in both flanges at one side of the valve to the inlet port V at the rear end of the cylinder to drive the piston forwardly. After the piston has passed and uncovered the exhaust port E there will be a considerable drop in pressure rearwardly of the piston. As a result, the pressure fluid flowing over the side of the valve will create a suction tending to move the valve to the right as Figure 1 is viewed.

As hereinbefore stated, the pressure areas X' are constantly exposed to pressure fluid. It follows, therefore, that when the piston overruns the free exhaust port D, the pressure fluid acting against the pressure areas X' on the left hand side of the valve will as-

- sist the suction of the pressure fluid flowing over the other side of the valve to throw the valve in the direction of the supply passage S. After the piston covers the free exhaust port D, the air entrapped in the front end of the cylinder will be compressed and such compressed air may then also assist the other forces in actuating the valve. However, the action of the valve is not dependent upon the air compressed by the piston. The sucking action exerted by the pressure fluid in flowing over the valve and the pressure fluid acting against the pressure areas X' being sufficient to throw the valve.
- In Figure 2 the piston is shown substantially at the end of its forward stroke ready to return on its rearward stroke and the valve is indicated as having moved to its opposite position to admit live pressure fluid to the forward end of the cylinder through the cylinder inlet port W. From this point in the operation of the device the cycle is repeated.

One of the advantages of this valve construction resides in the fact that the seating surfaces of the valve are longer than the seating surfaces of a round or spool valve having substantially the same surface area subject to pressure and in consequence the valve of the present invention may have the minimum travel for a given valve opening.

I claim:

1. A fluid actuated rock drill, comprising a cylinder and reciprocating piston, a water tube extending through the piston, a free exhaust port located centrally of the cylinder and controlled only by the piston, a fluid distributing valve in the form of a rectangular slideable block located rearwardly of the cylinder around the water tube, opposed pressure areas on the sides of the valve constantly exposed to pressure fluid for throwing the valve, and inlet ports for the ends of the cylinder controlled only by said valve.
2. A fluid actuated rock drill, comprising a cylinder and reciprocating piston, a water tube extending through the piston, a free exhaust port located centrally of the cylinder and controlled only by the piston, a fluid distributing valve in the form of a rectangular slideable block located rearwardly of the cylinder around the water tube, said valve having a central aperture through which the water tube extends, op-

posed pressure areas on the sides of the valve constantly exposed to pressure fluid for throwing the valve, and inlet ports for the ends of the cylinder controlled only by said valve.

3. A fluid actuated rock drill, comprising a cylinder and reciprocating piston, a water tube extending through the piston, a free exhaust port located centrally of the cylinder and controlled only by the piston, a valve box located rearwardly of the cylinder and having a rectangular valve chamber, a distributing valve in said box in the form of a rectangular slideable block having an open central portion encircling the water tube, opposed symmetrical pressure areas on the sides of the valve constantly exposed to pressure fluid for throwing the valve, and inlet ports for the ends of the cylinder controlled only by said valve.

4. A fluid actuated rock drill, comprising a cylinder and reciprocating piston, a water tube extending through the piston, a free exhaust port located centrally of the cylinder and controlled only by the piston, a valve box located rearwardly of the cylinder and having a rectangular valve chamber, a distributing valve in said box in the form of a rectangular slideable block having an open central portion encircling the water tube, said valve being reciprocable in a plane extending transversely through the water tube and of appreciably greater length than width, and the longer sides forming the surfaces of the valve alternately exposed to reduced pressure, and inlet ports for the ends of the cylinder controlled only by said valve.

5. A fluid actuated rock drill, comprising a cylinder and reciprocating piston, a water tube extending through the piston, a sleeve around the water tube, a free exhaust port located centrally of the cylinder and controlled only by the piston, a fluid distributing valve in the form of a rectangular block located rearwardly of the cylinder around the water tube sleeve, said valve being reciprocable in a plane extending transversely through the sleeve, and inlet ports for the ends of the cylinder controlled only by said valve.

In testimony whereof I have signed this specification.

CHARLES C. HANSEN.
